INTERNAL COMBUSTION ENGINE

Herbert W. Houston, North Hollywood, Calif.

Application July 20, 1929, Serial No. 379,772

15 Claims. (CL. 123—58)

My invention relates to internal-combustion engines and in particular to a cam engine which finds special utility in the field of air transportation. My invention is particularly adapted to two-cycle engines and in this connection will be explained in the ensuing description, but it should be understood that certain features of my invention are adapted to other types of engines.

It is an object of my invention to provide a two-cycle engine which is more efficient than certain present engines, thus adapting it to aircraft use. I prefer to accomplish this object by providing a two-cycle engine in which the scavenging of the spent gases from the cylinders is more efficient, thus increasing the overall efficiency.

One way in which the scavenging of the spent gases may be made more efficient is by holding the piston in a retracted position for a greater length of time thus allowing the fresh air to more completely expel the spent gases from the cylinder.

It is another object of my invention to provide a two-cycle engine which is operable by a cam-operating means in which the shape of the cam may be designed so that the piston is held in a retracted position for a material length of time whereby better scavenging of the burned gases is secured.

Another way in which a better scavenging action may be secured is by introducing into the cylinder, air which has been highly compressed, thus more completely blowing out the spent gases in the cylinder.

It is a further object of my invention to provide a two-cycle engine of the above type which employs a novel method of compressing air on the retracted stroke of the piston so as to secure a better scavenging action.

It is another object of my invention to provide a novel method of securing for the air to be compressed an initial pressure which is slightly above atmospheric, thus securing a supercharging effect.

My invention also relates to Diesel engines. Diesel engines are ordinarily operated by compressing a quantity of air in a cylinder to a high pressure and a high temperature, and introducing a charge of fuel into the compressed air, the fuel being ignited by contact with the high temperature of the air and burning to provide a high pressure of gases in the cylinder which in expanding moves a piston in the cylinder and provides the power. The speed of ordinary Diesel engines is limited due to the fact that the fuel used is relatively slow-burning and the pressure and the temperature in the cylinder during expansion

must be maintained at sufficiently high values to support combustion of the fuel. This means that the piston must not be retracted in the cylinder at such a rate that the burning gases are cooled sufficiently to stop combustion.

It is also an object of my invention to provide a Diesel engine in which the shaft speed thereof may be greatly increased without retracting the piston in the cylinder at such a rate as to stop combustion of the fuel.

It is also an object of my invention to provide an engine in which the duration of the expansion stroke is relatively long as compared to the other strokes of the cycle.

It is another object of my invention to provide a two-cycle Diesel cam engine with increased speed and efficiency.

It is also an object of my invention to provide a novel injector for injecting fuel into an engine so as to mix the fuel with the air in the cylinder as the fuel is injected.

It is also an object of my invention to provide a novel type of fuel pump for an engine which may be adjusted to pump a definite charge of fuel into the cylinder.

Further objects of my invention reside in the particular details of construction as will be explained in the ensuing description.

In the attached drawings I have illustrated a preferred form of my invention, but it should be understood that I am not limited to the form shown therein. In the drawings:

Fig. 1 is an end view of a portion of my invention showing the arrangement of the parts, certain of the parts being in section.

Fig. 2 is a partial sectional view taken on the line 2—2 of Fig. 1, showing a side elevation of my device.

Fig. 3 is a sectional view taken as indicated by the line 3—3 of Fig. 2 showing a fuel pump of my invention.

Fig. 4 is a section taken on the line 4—4 of Fig. 3.

Fig. 5 is a fragmentary view of a fuel injector shown in Fig. 2.

Fig. 6 is an alternative form of fuel injector.

Fig. 7 is a development of the fuel pump assembly and its associated cams.

Fig. 8 is a development of the main cam showing the positions of the pistons.

Fig. 9 represents indicator diagrams illustrating the operation of my engine as compared with other types of engines.

In the present application I have shown certain features of construction that are shown and ex-

plained in detail in my co-pending application entitled Variable stroke cam engine, Serial No. 320,579, filed November 20, 1928, Patent No. 1,810,017 issued June 16, 1931. For a complete detailed explanation of these features, reference should be had to the application supra.

Referring to Fig. 2, my engine consists of a supporting structure indicated by the numeral 11, which consists of a circular rear crank case member 12 and a forward web structure 13 which are held in spaced relationship by studs or cross-head guides 14. Formed in the forward web structure 13 is a plurality of openings 15, the openings 15 being grouped around the center of the web structure 13 and positioned between and in alternate relationship with the several cross-head guides 14. Adjacent the forward web structure 13 and extending in the direction of the rear crank case member 12 is a cylindrical member 16 which has cupped portions 17 that are received by the openings 15, the member 16 being secured to the web structure 13 by attaching bolts 21 which pass through the web structure 13 and into flanges 20 around the cupped portions 17. Secured to the cylindrical member 16 and to the rear crank case member 12 is a perimetric dust plate 24 which excludes dust from the interior of the crank case thus formed and retains lubrication therein.

A sleeve 25 extends rearwardly from the center of the forward web structure 13 and is provided with a central bore 26 which is axially parallel with the cross-head guides 14. In the forward end of the sleeve 25 is a counterbore 27 which receives the outer race of a bearing 28. In axial alignment with the bore 26 is a bore 30 in the rear crank case member 12, which bore 30 receives the outer race of a bearing 31.

Journalized by the inner races of the bearings 28 and 31 is a main shaft 32, the forward end of which extends outside the engine and may be connected to a propeller or other power-taking device (not shown). Around the shaft 32 to the rear of the sleeve 25 is a thrust bearing 34, a forward race of which contacts the rear end of the sleeve 25, and a rear race of which contacts a hub 35 of a drive cam 36, the hub 35 being rigidly keyed to the shaft 32 and being clamped in position by a nut 37 which is threaded on the shaft 32. The cam 36 has cam faces 38 which are shaped in a manner to be hereinafter described and is provided with an annular rearward projecting skirt 39. Positioned between the projecting skirt 39 and the rear crank case member 12 is a double thrust bearing 39a, the bearing 39a having a double race so as to reduce the ball speed thereof in a manner described in my application supra.

Secured to the forward web structure 13 in abutting relationship with one of the cupped portions 17 is a cylinder member 40 which is separated only by a gasket 41 from the cupped portion and cooperates therewith to form a continuous cylinder 42 which is closed at the forward end by a cylinder head 43 and at the rear end by a wall 44 formed at the rear of each of the cupped portions 17. The cylinder member 40 is provided with a flange 46 through which the bolts 21 are passed for securing the cylinder member 40 to the forward web structure 13 and for clamping the gasket 41 between the abutting edges of each of the cupped portions 17 and the cylinder members 40. A piston 50 is slidable in the cylinder 42 to a forward or advanced position and to a rear or retracted position and divides the cylinder 42 into a forward power-producing chamber 51 and a rear air compression chamber 52. Intake pas-

sages 53 are formed through the walls of the cylindrical member 16 and communicate between the compression chamber 52 and a chamber 54 formed in the walls of the cylindrical member 16. A horn 56 is secured to the exterior of the cylindrical member 16 around the opening to the chamber 54 by screws 57 which extend through a flange 58 formed on the horn 56, the horn 56 having a mouth-opening 60 which extends toward the forward end of the engine. Openings 61 through a web portion 62 of the horn 56 are closed by an intake valve disc 63 which rests thereagainst by the action of a spring 64 to form an intake valve.

When my motor is used with a propeller, the mouth 60 of the horn 56 is in the air stream of the propeller which is attached at the forward end of the shaft 42 so that the air-compression chamber 52 receives air through the intake valve at a pressure slightly greater than atmospheric. The air thus received into the compression chamber 52 is adapted to be compressed therein by the piston 50 as the piston 50 moves from an advanced to a retracted position. When the piston 50 is retracted so that the top of the piston uncovers a mouth 67 of a by-pass port 66 the compressed air is discharged through this port. This allows the compressed gas to pass from the compression chamber 52 to the power-producing chamber 51 where it exerts a scavenging effect on any spent gases which may be in the power-producing chamber 51. To aid this scavenging action I provide a gas deflector wall 68 which deflects the compressed air entering the power-producing chamber 51 from the by-pass port 66 toward the cylinder head 43, thus forcing the spent gases out through an exhaust port 70 formed through the walls of the cylinder member 40 opposite the mouth 67 of the by-pass port 66. The piston 50 provides extending legs 71 which always close the mouth 67 of the by-pass port 66 and the exhaust port 70 except when the piston 50 is in an extreme retracted position, the legs 71 being of such length that they do not prevent entrance of the air from the compression chamber 52 to the by-pass port 66 when the piston 50 is in a retracted position. This permits communication between the compression chamber 52 and the power-producing chamber 51 when the piston 50 is in a fully retracted position.

I have described only one of my cylinder assemblies, but have shown my engine as having six such assemblies, it being understood that more or fewer may be used as desired.

The piston 50 is moved into the retracted and advanced positions by a piston rod 72 which is threaded to the piston 50 and extends rearwardly through a central opening 73 in a sleeve 74 which is formed on the wall 44 and projects forwardly into the cylinder 42. Packing 76 is provided between the walls of the opening 73 and the piston rod 72 so as to form a hermetically tight joint therebetween. The rearward end of the piston rod 72 is provided with cross-head arms (not shown) which slidably contact the cross-head guides 14 and are guided thereby. Inner races of bearings 78 and 79 are carried by pins 80 and 81 formed on the rearward end of the piston rod 72 and outer races of the bearings 78 and 79 contact forward and rear faces 38 of the drive cam 36. This cross-head and bearing construction is more specifically described in my co-pending application supra.

It should be noted that I position the openings 15 in the forward web structure 13 so that suffi-

cient space is left between the shaft 32 and the cylinder members 40 to allow cooling air to circulate around cooling fins 83 formed on the cylinder members 40 and to provide for installing a plurality of fuel pumps 84 of my invention in this space.

I prefer to provide one of the fuel pumps 84 for each of the cylinders 42 and to operate the fuel pump once for every revolution of the shaft 32 so as to inject fuel into the cylinder 42 at the correct time. However, it should be understood that I am not confined to this arrangement as it is possible to provide only one fuel pump and have this fuel pump operated so as to inject fuel into each of the cylinders at the proper time. Where a fuel pump is provided for each of the cylinders as is shown in the attached drawings, I provide a forwardly projecting cylinder 85 which is formed on the forward web structure 13 and which 20 threaded supports an adjusting nut 86, the adjusting nut 86 being rotatable on a cylindrical body 87 between a rear shoulder 88 and a forward attaching nut 89. The cylindrical body 87 surrounds the shaft 32 and is keyed to the sleeve 25 85 as indicated by the numeral 90, so that as the adjusting nut 86 is turned, a relative motion occurs between the adjusting nut 86 and the body 87, and the body 87 is moved along the shaft 32.

In the body 87 are the fuel pumps 84 of my invention, each of which consists of a hole bored through the body 87 between the cylinder member 40 and the shaft 32 and providing a cylinder 92 in which is slidably a piston 93 which provides a pumping chamber 94 in the cylinder 92 forward of the piston 93. The rear end of the piston 93 extends through a counterbore 95 and a fluid-tight joint is formed therebetween by a packing member 96 which is retained in place by a nut 97 threaded in the counterbore 95. A spring 98 is 35 compressed between the nut 97 and a collar 100 formed on the rear end of the piston 93 and normally tends to move the piston 93 in a rearward direction, the piston 93 being retained in the cylinder 92 by a retaining nut 101 threaded in the 40 counterbore 95.

Secured to the shaft 32 to the rear of the body 87 is a cam plate 102 having a fuel pump cam 103 which has a single hump and which engages a roller 104 on the rear end of the piston 93 so as to move the piston 93 forwardly and backwardly once for each revolution of the shaft 32. As the piston 93 is moved rearwardly in the cylinder 92, a charge of fuel is drawn into the pumping chamber 94 from a fuel tank (not shown) through an inlet pipe 106 in which is a check valve 107. As the piston 93 is moved forwardly, the fuel in the pumping chamber 94 is forced outwardly through a discharge outlet, and outlet pipe 108, past a check valve 109, and is injected into the power-producing chamber 51 through an injector 110. The fuel continues to be injected into the power-producing chamber 51 until communication is established between the pumping chamber 94 and the fuel tank through a by-pass opening 112 which permits the fuel in the pumping chamber 94 to return to the fuel tank instead of being forced into the chamber 51.

In the by-pass opening 112 of each of the fuel pumps 84, I provide a by-pass valve 113 of my invention which consists of a guide-opening 114 in the form of a hole which is drilled in the body 87 between a pair of the fuel pumps 84. Slidable in the guide-opening 114 is a valve rod 115 having a 75 valve head 116 at the forward end which seats

in a valve seat formed by a counterbore 117 in the body 87.

Threaded in the counterbore 117 is a nut 118 containing a spring 119 which normally forces a pin 120 into contact with the valve head 116 so as to normally maintain the valve 113 in a seated position. The valve 113 is operated by a valve cam 122 formed on the cam plate 102 which engages a roller 123 on the rear end of the piston rod 115 so as to open and close the valve 113. When the valve 113 is opened, communication is established between a chamber 124 formed in the counterbore 117 between the valve head 116 and the nut 118, and a chamber 125 formed by the walls of the guide-opening 114, and an annular groove 15 126 formed on the valve rod 115 to the rear of the valve head 116. The chamber 124 is in communication with the by-pass opening 112 so that when the valve 113 is opened fuel may pass from the fuel pump, through the by-pass opening 112, 20 to the chamber 124 past the valve 113, into the chamber 125, and out through the outlet opening 127 which communicates between the chamber 125 and the fuel tank.

It should be noted that by turning the adjusting nut 86 so as to move the body 87 in a forward direction the roller 123 on the by-pass valve 113 is contacted by the valve cam 122 at a later time which means that fuel is injected into the cylinder 42 by the fuel pump for a greater length of 30 time. As the adjusting nut 86 is turned so that the body 87 is moved in a rearward direction the roller 123 contacts the valve cam 122 at an earlier time which causes fuel to be injected into the cylinder 42 for a shorter period of time and a 35 smaller charge is thus injected into the cylinder 42. The adjusting nut 86 thus provides a means for adjusting both the duration of injecting fuel into the cylinder 42 and the amount of fuel injected therein. 40

It will be noted by referring to Fig. 7 that I proportion the size of the parts of my pump and by-pass valve so that the roller 104 on the pump is always in contact with the cam 103 even when the body 87 is moved to its extreme forward position, while the roller 123 on the by-pass valve does not contact the cam 122 except when operated thereby. This provides for changing the opening of the by-pass valve so as to pump to the cylinder 42 a smaller charge of fuel when the 50 body 87 is moved forward and a greater charge of fuel when the body 87 is moved backward. 45

The fuel which is pumped by the fuel pumps 84 is injected through the injector 110 as explained before. In order to thoroughly mix the 55 fuel which is injected into the cylinder with the air which is in the cylinder and thus provide better combustion, I provide a novel type of injector which is shown in enlarged form in Fig. 5. The injector 110 consists of an injector body 128 60 which is threaded in a flanged nut 129 threadedly inserted in the cylinder head 43. The outlet pipe 108 of the fuel pump communicates with an opening 130 in the flanged nut 129 and the discharge end of the opening 130 is formed into a 65 nozzle 131 which nozzle 131 directs the fuel through a restricted throat 132 of an opening 133 formed in the body 128. Surrounding the opening 133 and parallel therewith is a plurality of air openings 134 which admit air to a central 70 opening 135 around the nozzle 131 so that air is drawn through the throat 132 as the fuel is injected therethrough, which intimately mixes the air and the fuel.

I prefer to provide the forward end of the pis- 75

ton 50 with a conical projection 136 positioned opposite the opening 132 so that as the mixture of air and fuel is injected into the cylinder 42 the mixture will be deflected by the conical projection 136 and directed toward the walls of the cylinder 42 so as to distribute the mixture evenly therein.

In the operation of my engine, the cam 36 moves the piston 50 from a retracted position to an advanced position which causes air to be drawn into the compression space 52 through the intake valve, the air being drawn in at a pressure slightly above atmospheric, as heretofore explained. As the piston 50 is moved from an advanced position to a retracted position the air in the compression space 52 is compressed, and when the mouth of the port 67 is uncovered the air in the compression space 52 is forced out through the by-pass port 66 to the power-producing chamber 51 and exerts a scavenging action on any spent gases therein. As the piston 50 is again moved from a retracted to an advanced position the air in the power-producing chamber 51 is compressed and at the correct time, determined by the timing of the engine, fuel pumped by the fuel pump 84 is injected through the injector 110 into the power-producing chamber 51. The fuel is ignited by contact with the high temperature of the air in the power-producing chamber 51 and burns to produce a greater gas pressure therein, which pressure forces the piston 50 from an advanced position to a retracted position to permit expansion of the gases.

Each time the piston 50 is moved from a retracted to an advanced position to define a compression stroke, air is drawn into the compression chamber 52 and the air in the power-producing chamber 51 is compressed, and each time that the piston is moved from an advanced position to a retracted position to define an expansion stroke, air is compressed in the compression chamber 52 and expansion of the gases in the chamber 51 occurs. While the piston is in a retracted position the air which has been compressed in the compression chamber 52 exerts a scavenging action and exhausts the spent gases from the power-producing chamber 51. This is a well known cycle of operation for a two-cycle engine.

As yet I have not described the particular contour of the cam surface 38 which moves the piston 50 in order to define the above strokes, but before describing this contour it is advisable to point out some of the limitations of the present crank type engines. All internal-combustion engines in which a piston is reciprocated by a crank on a crank shaft are limited to a piston motion in which the piston has a compression and an expansion stroke of the same duration. This limits the shaft speed of a Diesel engine to a speed determined by the maximum speed at which the piston may be retracted in the cylinder, as explained before, it being necessary to withdraw the piston in the cylinder at a sufficiently slow rate of speed that the pressure in the cylinder will not be decreased sufficiently to cool the burning gases therein below the combustion point.

In a crank type engine of the two-cycle type, the piston is retained in the retracted position for a very short period of time due to the substantially harmonic motion of the piston and thus incomplete scavenging of the gases in the cylinder results.

In a cam engine of the type described above, the cam may be so designed as to give to the

piston any required movement. Thus it is possible to design the cam so that the piston will be moved with a relatively quick compression stroke, a slow power stroke, and may be left in the retracted position for a sufficient length of time to secure a greater efficiency in scavenging the gases. In Fig. 8 I have illustrated the development of a cam which is designed to impart to a piston a movement as defined above. In this figure I represent the bearings 79 by circles 140 and the bearings 78 by circles 141. The bearings 79 and 78 are shown by the circles 140 and 141 as moved to a plurality of equally spaced positions 142, 143, 144, 145, 146 and 147. The contours of the forward and rear surfaces 38 of the cam 36 which engage the bearings 79 and 78 are represented by the lines 150 and 151.

When the bearings 79 and 78 are in a position 142 represented by circles 140 and 141, the piston 50 is in the extremely retracted position, and as the bearings 79 and 78 move through the successive positions the piston is moved to an extremely advanced position which position is shown as being between positions 144 and 145 and returned to a retracted position to define a complete cycle.

As the piston 50 is directly connected by the piston rod 72 to the bearings 79 and 78, the motion of the bearings 79 and 78 is directly transmitted to the piston and the motion of the piston is therefore the same as the motion of these bearings. I have accordingly drawn a line 152 through the centers of the circles 140 in the various positions and this line 152 can therefore be considered as being indicative of the movement of the piston 50, and the piston 50 will therefore be referred to as having a motion corresponding to this line. When the piston 50 is moved from the position 142 and reaches a position indicated by a position 154, intermediate the positions 142 and 143, the top of the piston 50 covers the mouth 67 of the by-pass port 66 and the compression stroke begins. The compression stroke continues during approximately 90° of rotation of the shaft 32 or until a position 155 is reached which is intermediate the positions 143 and 144. At this time fuel is introduced into the cylinder in a manner previously explained and the power of the expansion stroke commences. The expansion stroke continues during 170° and through positions 144, 145 and 146 until a position 156 is reached which is intermediate positions 146 and 147, at which position the forward end of the piston 50 uncovers the mouth 67 of the by-pass port 66 and the air which has been compressed in the compression chamber 52 is by-passed into the power-producing chamber 51 and the exhaust interval commences, this interval ending when the piston again closes the mouth 67.

I design the cam 36 so that the piston is held in a retracted position between the positions 156 and 154 for 100° of rotation of the shaft 32 which is for the purpose of more completely scavenging the gases from the cylinder. It will thus be seen that a complete cycle of operation for the piston is accomplished for every revolution of the shaft 32. The set of operating conditions outlined above provides a cam having a contour as indicated in Fig. 8. Another set of operating conditions which will give good results is an expansion cycle of 210°, a lag or exhaust cycle of 40°, and a compression cycle of 110°. Various other contours may be given to the cam so as to secure any required set of operating conditions, it being only necessary to ascertain what operating conditions

are wanted and design the cam to give the required movement to the piston 50.

In Fig. 9 I have illustrated some indicator diagrams such as could be obtained with different 5 cams, these diagrams being compared with indicator diagrams of various other types of engines. Diagrams A and B are diagrams such as can be obtained by a cam engine of my design having different shapes of cams. Diagram C is an indicator diagram of another type of Diesel engine, diagram D is taken from a conventional gasoline engine, and diagram E from a conventional steam engine.

It is a well known fact that the area enclosed 15 by the lines of an indicator diagram is representative of the power which is provided by the combustion of the gases in the cylinder. The amount of power available at the shaft of the engine being determined by the mechanical efficiency of the engine, those engines of equal mechanical efficiency provide the greatest shaft 20 horse-power which have the greatest area enclosed by the lines of the indicator diagram.

It will be noted from a study of the diagrams 25 shown in Fig. 9 that the lengthening out of the time for the expansion stroke is of considerable advantage in providing a much larger area in an indicator diagram. Another advantage of having a long power stroke is that with the same 30 shaft speed of Diesel engine, a cam type engine having a long power or expansion stroke is able to use a cheaper and longer burning oil than a conventional engine of the crank type having a uniform time for the compression and expansion 35 strokes.

It will be noted that the placing of the mouth 40 of the intake valve in the air stream of the propeller provides an initial pressure on the air in the air-compression chamber, and the provision of a smaller space in which the air is compressed during the expansion stroke provides a much higher pressure for the air and this air is therefore better able to scavenge the gases from the cylinder.

45 The use of the deflector wall 68 is effective in distributing the incoming air toward the top of the cylinder 42 so as to better scavenge the gases therefrom and the maintaining of the piston 50 in a retracted position for a longer period of time 50 provides a better scavenging action for the gases. The use of the injector 110 of my invention is responsible for a more complete mixture of the fuel with the air in the cylinder 42 which secures more complete combustion of the gases.

55 Although I have explained and illustrated the pump of my invention as being used to pump fuel to the cylinder, I am not limited to this use as my pump has utility in other ways. For example, my pump is also useful in pumping lubricating oil to the moving parts of the engine and in other capacities.

In Fig. 6 I have shown an alternative form of injector which operates on the same principle as the form shown in Fig. 5 but which has certain 65 advantages with different fuels. In the form of the injector shown in Fig. 6 a nozzle 160 is formed on the flanged nut 129 which is similar to the nozzle 131 with the exception that the nozzle 160 extends a short distance into the cylinder 70 42. An injector body 161 is threaded into the flanged nut 129 and is provided with an opening 162 in alignment with the opening through the nozzle 160 and which has a throat 163. Air openings 164 through the injector body 161 permit 75 air to enter to a central opening 165 in the in-

jector body 161 around the nozzle 160, but unlike the openings 134 in the preferred form of my injector, the openings 164 are formed at an angle to the opening 162.

With this alternative form of my injector, a 5 different contour on the forward end of the piston is more advantageous in securing a proper distribution of the mixture to the cylinder 42, and I therefore provide a projecting ring 166 having a depression between the edges thereof, 10 such contour on the head of the piston 50 being particularly advantageous with the alternative form of my injector.

It should be clear that certain features of my 15 invention are not limited to the particular form of two-cycle Diesel engine which I have explained in this description but may be applied to various other engines. If it is desired to make a gasoline engine in place of a Diesel engine, the main shaft 32 may be made hollow and the combustible gases taken into the engine through the hollow shaft. A jacket surrounding openings in the shaft and communicating with the air-compression chamber permits introduction of the combustible gases into the cylinder 42. A similar 20 arrangement is explained in my co-pending application supra. This and other modifications can be made without departing from the spirit of my invention as defined by the appended claims.

I claim as my invention:

1. In an engine, the combination of: a main 30 shaft, walls defining a cylinder axially parallel with said shaft; a piston slidable in said cylinder to an advanced position and to a retracted position; and means for controlling the movement of said piston, said means moving said piston from a retracted position to an advanced position to define a compression stroke, moving said piston from an advanced position to a retracted position to define an expansion stroke, and holding 40 said piston in a retracted position to define an exhausting interval, said expansion stroke occurring during a longer interval of time than said compression stroke, and said exhausting interval being of approximately equal duration to said 45 compression cycle.

2. In an engine, the combination of: a main 50 shaft, a cylinder mounted with its longitudinal axis parallel with said shaft; a piston slidable in said cylinder and adapted to be reciprocated therein with a power and a compression stroke; and means for controlling the movement of said piston and for holding said piston stationary during a substantial portion of the operating cycle to provide a prolonged exhaust interval. 55

3. In an engine, the combination of: a main shaft, a cylinder mounted with its longitudinal axis parallel with said shaft; a piston slidable in said cylinder through successive compression and power strokes; and means for controlling the movement of said piston and for positively holding said piston stationary for a substantial length of time between the end of a power stroke and the beginning of a succeeding compression stroke to provide a prolonged exhaust interval. 65

4. In a cam-engine, the combination of: a main shaft, a cylinder mounted with its longitudinal axis parallel with said shaft; a piston slidable in said cylinder; and a cam on said shaft and radial thereto for controlling the movement of said piston, said cam having a dwell extending throughout a sufficient portion of the cam cycle to hold said piston stationary during a substantial portion of the operating cycle to provide a prolonged 70 exhaust interval. 75

5. In a cam-engine, the combination of: a main shaft, a cylinder mounted with its longitudinal axis parallel with said shaft; a piston slideable in said cylinder; and a cam on said shaft and radial thereto for controlling the movement of said piston, said cam having a dwell extending throughout a sufficient portion of the cam cycle to positively hold said piston stationary at the end of a power stroke thereof and during a substantial portion of the operating cycle to provide a prolonged exhaust interval. 5
6. In a cam-engine, the combination of: a main shaft, a cylinder mounted with its longitudinal axis parallel with said shaft; a piston slideable in said cylinder through successive power and compression strokes; and a cam on said shaft and connected with said piston for controlling the movement of said piston, said cam having a dwell extending throughout a sufficient portion of the cam cycle to hold said piston stationary for a substantial length of time between the end of a power stroke and the beginning of a succeeding compression stroke to provide a prolonged exhaust interval. 10
15. 7. In a cam-engine, the combination of: a main shaft, a cylinder mounted with its longitudinal axis parallel with said shaft; a piston slideable in said cylinder; and a cam for controlling the movement of said piston, said cam having a power portion cooperating with said piston during an expansion stroke thereof; a compression portion for moving said piston through a compression stroke, and an intermediate exhaust portion having a dwell extending throughout a sufficient portion of the cam cycle to hold said piston stationary a substantial length of time between the end of an expansion stroke and the beginning of a compression stroke to provide a prolonged exhaust period. 25
20. 8. A cam-engine as defined in claim 7 in which the compression portion of said cam extends throughout a sufficient portion of the cam cycle to provide a relatively quick compression stroke of the piston and in which the expansion portion of said cam extends throughout a sufficient portion of the cam cycle to provide a relatively slow expansion stroke of said piston. 30
25. 9. A cam-engine as defined in claim 7 in which the extent of the expansion portion of the cam in the cam cycle is approximately twice that of the compression portion of said cam. 35
30. 10. A cam-engine as defined in claim 7 in which the extent of the exhaust portion of the cam in the cam cycle is approximately equal to that of the compression portion of said cam. 40
35. 11. In a two-cycle internal-combustion engine, the combination of: a main shaft, a cylinder axially parallel with said shaft and having an exhaust port and an intake port; a piston slideable in said cylinder through successive compression and power strokes and adapted to open said ports at the end of a power stroke and to close said ports at the beginning of a succeeding compression stroke; and means including an operative connection between said piston and said 45
50. shaft, for controlling the movement of said piston and for positively holding said piston stationary for a substantial length of time between the end of said power stroke and the beginning of the succeeding compression stroke and while said ports are open so as to provide a prolonged scavenging interval. 5
55. 12. In a two-cycle internal-combustion cam-engine, the combination of: a main shaft, a cylinder axially parallel with said shaft and having an exhaust port and an intake port; a piston slideable in said cylinder; and a cam for controlling the movement of said piston, said cam having a dwell extending throughout a sufficient portion of the cam cycle to hold said piston stationary while said ports are open and during a substantial portion of the operating cycle to provide a prolonged scavenging interval. 10
60. 13. In a two-cycle internal-combustion cam-engine, the combination of: a main shaft, a cylinder having an exhaust port and an intake port; a piston slideable in said cylinder through successive compression and power strokes in a path parallel with said shaft and adapted to open said ports at the end of a power stroke and to close said ports at the beginning of a succeeding compression stroke; and a cam for controlling the movement of said piston and having a dwell extending throughout a sufficient portion of the cam cycle to positively hold said piston stationary for a substantial length of time between the end of a power stroke and the beginning of a succeeding compression stroke to provide a prolonged scavenging interval. 15
65. 14. In a two-cycle internal-combustion cam-engine, the combination of: a crank shaft, a cylinder having an exhaust port and an intake port; a piston slideable in said cylinder parallel with said shaft through successive compression and power strokes and adapted to open said ports at the end of a power stroke and to close said ports at the beginning of a succeeding compression stroke; and a cam for controlling the movement of said piston, said cam having a power portion cooperating with said piston during an expansion stroke thereof, a compression portion for moving said piston through a compression stroke, and an intermediate exhaust portion having a dwell extending throughout a sufficient portion of the cam cycle to hold said piston stationary for a substantial length of time between the end of a power stroke and the beginning of a succeeding compression stroke to provide a prolonged scavenging interval. 20
70. 15. An engine as defined in claim 13 in which the power portion of the cam extends throughout a relatively large portion of the cam cycle, in which the compression portion of said cam extends throughout a substantially smaller portion of the cam cycle, and in which the exhaust portion of said cam extends throughout a portion of the cam cycle approximately equal to the extent of the compression portion of said cam. 25
